UNITED STATES PATENT OFFICE.

AUGUST ABEL, OF LEIPZIG, GERMANY, ASSIGNOR TO THE FIRM ATLAS-WERKE POHLER & CO., OF LEIPZIG-STOTTERITZ, GERMANY.

DEVICE FOR CHARGING AND DISCHARGING COMPRESSED-AIR CONTAINERS.

Application filed April 23, 1926, Serial No. 104,240, and in Germany March 17, 1925.

This invention relates to a device by means of which a compressed air conduit may be brought into communication with a number of containers arranged to pass the device, with the object of releasing the air previously admitted into the said containers and to admit fresh air if required. These effects are obtained by the particular arrangement of the controlling device according to the invention, which mainly consists of two valves of which one is at the end of the supply conduit while the other is on the container and movable therewith. Each of the containers is provided with one of such valves and the mutual adjustment of the valves is effected while the connection of the supply conduit with the container is being established. A patent for this invention has been applied for in Germany, 20 March 17, 1927.

The device according to the invention may be employed for various purposes, as for example on compressed air operated presses which are used in the manufacture of boots and shoes for cementing or otherwise laying the soles to the shoes. These presses, as is known, are provided with inflatable pads and as the novel device is able to act as inlet as well as outlet valve, only one of such valves is required whereas two were necessary in the hitherto known arrangements.

The device according to the invention offers particular advantages in such presses in which the individual pressing places are arranged upon rotary carriers of either table or drum shape, and in which the connecting means of the said pressing places, or pressing pads respectively, are successively moved to a place opposite the supply conduit.

A further advantage of the device according to the invention rests in the elimination of any packing means or the like, and in the great simplicity of construction generally as will be apparent from the following description of the accompanying drawing in which the invention is illustrated by way of example.

Fig. 1 shows the co-operative valves in longitudinal section in their position of rest.

Fig. 2 is a similar section showing the valve of the pressing pad in emptying position.

Fig. 3 illustrates by a similar section the filling or refilling position of the valves.

Fig. 4 is a cross section on line 4—4 of Fig. 1.

Fig. 5 illustrates the application of the device to a rotary table press on which, for the sake of clearness, only one pressing pad is shown in position.

Referring briefly to Fig. 5, the rotary table 1 is provided along its circumference with a number of shoe presses each comprising an air cushion or pneumatic pad 14 as shown on the right hand side of the figure. Each of these pads communicates by means of a tube 13 with a valve 2 below the table top which serves as inlet and outlet for the compressed air. Within the casing of this valve (Figs. 1 to 3) is a cylindrical body 16 adapted to move in vertical direction, said cylindrical body extending at its lower end into a conical valve surface 3 and having grooves 17 spaced around its cylindrical circumference for the passage of the compressed air. The said valve body is normally held upon its seat by the pressure of the air within the pad but, if required, a spring may be provided in addition.

At one place of the table below the top thereof a filling or supply valve 5 is arranged which is supported by an arm 12 of the machine frame and adapted to move in vertical direction. Within the casing of this valve a cone 8 is provided which normally is pressed upward against its seat by the action of a spring 10. Compressed air is admitted into the valve at 7 by means of a flexible tube which is not shown in the drawing. The valve 5 is attached to the upper end of a rod 11 guided within a bore of the arm 12 and whose lower end is connected to one arm of a foot lever 15, the actuation of which causes the valve 5 to be raised and lowered as required.

The mode of operation of the device is as follows: When the machine is at rest the foot lever 15 takes the position shown at a—a in Fig. 5, in which position the valves 2 and 5 are a slight distance apart from each other, it being understood that the table top has previously been turned so that one of the valves 2 of the pressing pads 14 is in opposition to the valve 5. Depressing the foot lever into the position marked b—b in Fig. 5 the valve is lifted just sufficiently for its cone 8 to press against the cone 3 of the valve 2 and to thus open it. Spring 10 must,

- of course, be strong enough to overcome the weight of the valve body 3 and the air pressure within the pad. Through the now open valve 2 (Fig. 2) the air is able to escape 5 from the pad 14 via the tube 18, passage 4 and the grooves 17 as indicated by the arrows in the said figure. If now the pad is to be refilled, or another pad filled, the foot lever must be depressed into its lowest position 10 *c—c*, which will cause the valve to be raised into its highest position (Fig. 3). In this position cone 3 of the valve 2 remains open, its lift being limited by a shoulder within the valve casing, or by the contracting 15 upper part thereof serving as such shoulder. It will be evident, thus, that the spring 10 of valve 5 becomes contracted on the further upward movement of valve 5, so that the valve cone 8 of the latter will be 20 pressed inwardly whereupon the passage for the compressed air from the conduit 7 to the pressing pad 14 is free, so that the latter may be inflated by the air moving in the direction of the arrows in Fig. 3. To prevent the escape of air the two contacting 25 valves 2 and 5 are tightened up against one another by a rubber washer 9 or the like positioned in a circular cavity at the top of valve 5.
- 30 In order to be able to fix the filling valve in the deflating position (corresponding to the treadle position *b—b* in Fig. 5), a resilient catch is provided consisting of a spring pin 18 adapted to engage with a 35 notch 19 of the rod 11 and to hold the rod and therewith the valve 5 in the corresponding position.

Although the invention has hereinbefore 40 been described as applied to a cementing press for use in the manufacture of boots and shoes, it is evident that I do not wish my invention limited to such presses but that it may be used in connection with other devices and for other purposes, whenever the 45 charging and discharging of compressed air containers by one single controlling device is of advantage.

What I claim is:

1. In a device for charging and discharging 50 a number of compressed air containers adapted to pass by and be arrested in working position, a valve on each of the containers, each valve including an enclosing casing and a cone protruding therethrough, a supply valve also including an enclosing casing and a cone protruding therethrough in alignment with the valve on the container when the two valves are brought into operative relation, and means for moving the 55 supply valve to thereby initially actuate a valve associated with one of the containers and upon continued movement thereafter to actuate said supply valve for refilling the container therefrom.
- 65 2. In a charging and discharging device

for a group of movable compressed air containers, a combined inlet and outlet valve on each of the containers, a supply valve separate therefrom and adapted to be moved in relation thereto, and means to first partly 70 and then fully press the supply valve against the said inlet and outlet valve so as to first exhaust and then refill the container.

3. A charging and discharging device for compressed air containers comprising two 75 valves movable in relation to each other, one valve being on the container and the other serving as a supply valve, valve cones in each of the valves protruding outwardly therefrom in opposition to each other, manually operated means to move the supply valve against the valve on the container and to depress the cone of the said container valve so as to release the air from the container, and to then depress the valve cone 80 of the supply valve to open same and refill the container.

4. In combination, a plurality of compressed air containers mounted on a movable support and each provided with a combined inlet and exhaust valve adapted to be brought successively into position for contact with a supply valve adapted to actuate the first named valves for exhausting and refilling the containers, a supply valve held 90 normally in a fixed position but movable toward and from the inlet and exhaust valve when the latter valve is brought into co-operative relation thereto; each of said valves including an enclosing casing and a cone 95 which protrudes through a valve-seating aperture therein and having associated therewith means for applying sufficient pressure to hold the valve normally closed; the pressure-applying means acting on the supply valve having greater power than the pressure-applying means acting on the inlet and exhaust valve; means for moving the supply valve into contact with the inlet and exhaust valve when brought into co-operative relation thereto and thereby opening the latter valve so as to permit the escape of air from the container, and means for arresting movement of the inlet and exhaust valve when opened, and for resisting 105 continued movement of the supply valve so as to cause the latter to open for co-operation with the inlet and exhaust valve in filling or refilling the container.

5. In a machine for charging and discharging successively a group of compressed air containers, a valve associated with each container adapted to operate alternately as an inlet valve for filling the container and as an outlet valve through which the container 115 may be emptied, a supply valve operable only in co-operation with one of the first named valves for refilling the container, and means for actuating said supply valve so as to first open a valve connected with a con- 120

125

130

tainer to empty the latter and then open the supply valve to refill the container by the combined action of the two valves.

6. In combination, a plurality of compressed air containers mounted on a rotatable support and each provided with a combined inlet and outlet valve; said valve being adapted to be brought successively into alignment with a subjacent supply valve for refilling the containers, a vertically movable supply valve held normally in a fixed position for co-operation with an aligned inlet and outlet valve, each of said valves including an enclosing casing and a cone which

15 protrudes through a valve-seating aperture therein and having associated therewith means for applying sufficient pressure to

hold the valve normally closed; the pressure-applying means acting on the supply valve having greater power than the pressure-applying means acting on the inlet and outlet valve, means for moving the supply valve into contact with and thereby opening an inlet and outlet valve when brought into co-operative relation thereto, and means for 20 limiting the opening movement of the inlet and outlet valve while permitting continued movement of the supply valve and thereby opening the latter valve for co-operation with the inlet and outlet valve in filling or 25 refilling the container.

In testimony whereof I affix my signature.

AUGUST ABEL.
